(57) **CLAIM**

I claim the ornamental design for a rectangular cake plate, as shown and described.

DESCRIPTION

FIG. 1 is a front view of a rectangular cake plate; and FIG. 2 is a back view of a rectangular cake plate; and FIG. 3 is a side view of a rectangular cake plate; and, FIG. 4 is a top view of a rectangular cake plate. The broken lines represent portions of the structure that form no part of the claim.
